CLAIM

The ornamental design for a light strip, as shown and described.

DESCRIPTION

FIG. 1 is a front view of a light strip, showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a perspective view shown in a condition of use. The broken lines shown in the drawings illustrate portions of the light strip, the additional broken lines in FIG. 8 illustrate environment; all broken lines form no part of the claim.

1 Claim, 8 Drawing Sheets
